Primary Examiner — Steven J Czyz(74) *Attorney, Agent, or Firm* — Paratus Law Group, PLLC(57) **CLAIM**

The ornamental design for a cover for earphone case, as shown and described.

DESCRIPTION

FIG. 1 is a front, top, and right side perspective view of a cover for earphone case, showing a first embodiment of my new design;

FIG. 2 is a front view of the first embodiment;

FIG. 3 is a back view of the first embodiment;

FIG. 4 is a left side view of the first embodiment;

FIG. 5 is a right side view of the first embodiment;

FIG. 6 is a top view of the first embodiment;

FIG. 7 is a bottom view of the first embodiment;

FIG. 8 is a back, top, and left side perspective view of the first embodiment; and,

FIG. 9 is a back, bottom, and left side perspective view of the first embodiment.

The broken lines depict portions of the article that form no part of the claimed design. The interior parts of the first embodiment, seen through openings in FIGS. 1, 3, 5, 7, 8, and 9, form no part of the claimed design.

1 Claim, 7 Drawing Sheets(56)
